MULTIPLE CENTRIFUGAL CASTING

Charles E. Sorensen, Detroit, and Russell H. McCarroll, Dearborn, Mich., assignors to Ford Motor Company, Dearborn, Mich., a corporation of Delaware

Application May 23, 1942, Serial No. 444,207

5 Claims. (Cl. 22—65)

This invention relates to production machines for centrifugal castings; and, more particularly, to a casting machine in which a plurality of different objects may be cast simultaneously by the application of centrifugal forces.

Numerous devices have been developed in the course of years to utilize centrifugal force in the casting of metallic objects. These have generally been of a type best exemplified by those used in casting flywheels and steel wheels in which the prime consideration was to obtain a dense and homogeneous periphery of the article while the central portion of the article was generally removed in finishing to permit its attachment to a shaft or axle. More lately, centrifugal casting has been extended to an ever-widening field. Many articles, however, which could be improved in some respects, if made by centrifugal casting, have not been so produced because a solid and uniform structure was required throughout and the available methods of centrifugal casting make it difficult to obtain this structure.

These earlier methods, as best illustrated in the casting of car wheels or pipes, provided for rotation of the mold about the axis of rotation of the article to be cast and thus obtained the desired peripheral structure. However, this limited the types of articles that could be cast and in many cases it required excessive rotational speed of the mold due to the relatively small diameter of the article. Further, the high speeds required limited the field to axially symmetrical articles to avoid severe stresses due to unbalanced loads; and but one article could be conveniently cast at one time. In the present method, the articles to be cast are arranged radially about the axis of rotation of the machine and revolve about that axis. They do not, then, have axial voids and are of uniform structure throughout. The rotational speed may be kept low because the radius, which determines the centrifugal force, is not dependent upon the dimensions of the object to be cast but merely on the location of it on the casting machine with reference to the axis of rotation. Nonsymmetrical articles may be cast and it is possible to cast a large number of objects at once.

The application of this method of casting to these problems and structure employed in carrying it out both possess the attributes of novelty and invention as demonstrated by the many advantages which flow from its use.

With these and other objects in view, the invention consists of the arrangement, construction and combination of various parts of the improved device, as described in the specification, claimed

in the claims and illustrated in the accompanying drawing in which:

Figure 1 is a plan view of a casting machine, certain portions being broken away to show the underlying structure.

Figure 2 is an elevation, portions thereof being shown in section as indicated by the line 2—2 on Figure 1.

Numeral 10 indicates generally a centrifugal casting machine which includes a pedestal 11, in which is journaled the spinner shaft 12 supporting the table 13. The shaft and the table are rotated by a beveled gear drive 14, the driving motor used not being shown. Secured to the top of the table 13 is a central ring 15 and adjacent the periphery and circumferentially spaced are a number of cradles 16 and hinge supports 17. Supported between each of the cradles 16 and the radially aligned portion of the central ring 15 is a semi-cylindrical lower mold support 18 having flanged edges 19 and pivotally mounted on each of the hinge supports 17 is a corresponding semi-cylindrical upper mold cover 20 with corresponding flanges 21.

25 The reservoir block 22 is seated in the central ring 15 and is made up of a number of individual block segments 23 of reinforced refractory material cemented together, as indicated at 24. Each of these segments has a gate 25 in its vertical wall; and, as best shown in Figure 2, it is interiorly shaped so that in co-operation with the other segments a basin 26 of considerable size and a seat 27 for a strainer disc 28 are formed.

30 The mold 29 which is outwardly cylindrical in form is received in the lower mold support 18 and, when the upper mold cover 20 is lowered in place, is entirely surrounded and protected by the metallic casing so formed. The mold 29 has an interior cavity 30 which in this case is used to mold a solid artillery shell. The mold 29 is likewise made of a baked refractory material which may be formed initially in two parts and joined together by cementing, but which preferably is molded integrally and includes the reinforcing

40 screen 32. When the mold is in place between the mold support and the mold cover, toggle locking means 33 are employed to hold the mold cover in close contact with the support during the casting operation. These clamps are shown in their closed position on the left side of Figure 1 and open on the right side.

45 In production, the mold cover 20 at each of the individual mold stations is opened, as shown at the right of Figure 2, and the molds 29 are placed in each of the lower mold supports 18. The pre-

assembled reservoir block 22 is then placed in the central ring and the size of these elements is so governed that a very close fit is obtained between the block and the abutting molds, these being proportioned slightly oversize so that tight contact is assured, and any excess material is readily removed at placement. The upper mold covers 20 are then put in the closed position, as shown on the left in Figure 2, and the toggles 33 are engaged and lock each of the molds into a closed unit. The table is rotated and the basin 26 of the reservoir 22 filled with molten metal which is, of course, projected by centrifugal force into each of the individual molds uniformly and under considerable pressure. After the metal has solidified, 10 rotation of the table is stopped and the molds are opened, at which time it will be found that the entire group of cast objects may be removed as a star-shaped unit preparatory to cutting off the sprues and cleaning. Similarly, the lower mold supports 18 may be lifted from their cradles for 20 cleaning; and, when replaced, the operation may be repeated.

Some of the advantages which flow from this construction are to be found in the provision of the large central basin used which permits a considerable source of molten metal to be accumulated prior to its projection to the interior of the mold. Moreover, all of the portions of the apparatus in contact with molten metal may be made of replaceable refractories and hence there is no delay for cleaning or disengaging the cast object from the mold, as is found when reusable molds such as those of rubber or metal are used. The provision of the hinged upper covers 20 present an additional safety factor in that if the covers should open during rotation, they will be in a position which will still retain the mold and the metal therein from flying out due to centrifugal force. The particular arrangement used is well adapted to production work in that a large number of the objects may be made at each casting and the cycle of operation is such that work may be readily removed and new molds placed.

Another advantage is to be found in the ease with which this equipment can be adapted to the casting of different articles. Any number of molds may be designed to fit the particular mold holders. Thus, by merely interchanging different molds, any number of different articles may be cast using the same machine, though it is advisable that in any one cycle, the same article be cast to keep the table properly balanced. As each of the mold stations is arranged radially and angularly separated, there is adequate provision for cooling and no difficulty is encountered on this score. It will be noted in Figure 2 that the lower mold support is spaced a considerable distance from the table, thus allowing free circulation of air around the entire structure. This, too, permits the continuous use of the apparatus in quantity production. It will be noted that this apparatus is particularly suited to the production of those objects which must be of uniform metallic constituency throughout. As the objects are spaced radially of the axis of rotation rather than aligned with it, as in the conventional car wheel, cast pipe or cylinder liner machines, there is no tendency to produce a hollow axial portion or pipe. It is preferable that sufficient metal be available to fill the molds, the sprues, and at least partially fill the basin of the reservoir to be drawn upon during cooling to prevent cooling

checks. Of course, if the metal remaining in the basin is to be drawn into the objects, it is essential that it remain in a semiliquid condition and this is permitted because of the large quantity of metal present and the fact that it is partially insulated against cooling by the relatively massive refractory walls of the reservoir. Since the article, as shown, has a relatively large section adjacent the gate, the metal in the gate, being between the article and the reservoir, is kept in a fluid condition by the heat from these two sources and continued flow of metal therethrough to the article is permitted as long as the latter requires it during the cooling stages.

Some changes may be made in the arrangement, construction and combination of the various parts of the improved device without departing from the spirit of the invention. It is the intention to cover by the claims such changes as may be reasonably included within the scope thereof.

The invention claimed is:

1. In a centrifugal casting machine, a horizontal table rotatably mounted, means to rotate said table, a reservoir support in the center of said table, a removable reservoir of refractory material received in said reservoir support, individual mold stations arranged radially of said table, including a cradle and a cover support, mold supports extending between said reservoir and said outer cradle, individual molds received in said mold support and in communication with said central reservoir, said molds being of refractory material, individual covers at each station hinged to said support and adapted to enclose said mold, and means to lock said covers in their closed positions.
2. In a centrifugal casting machine, a horizontal table rotatably mounted, means to rotate said table, means disposed centrally of said table to receive a replaceable reservoir of refractory material, said reservoir including a basin of substantial size and having gates through the walls thereof circumferentially spaced, a plurality of mold stations radially arranged on said table aligning with the gates in said reservoir, mold supports at said mold stations, replaceable molds of refractory material received in said supports and in communication with said gates, means hinged adjacent the outer edge of said table at said mold stations and adapted to enclose said molds, and means to lock said mold covers in their closed positions.
3. In a centrifugal casting machine, a horizontal table rotatably mounted, means to rotate said table, retaining means centrally disposed on said table, a replaceable reservoir block of refractory material received in said retaining means, said reservoir having a basin of substantial capacity and gates leading therethrough at spaced intervals therethrough, a plurality of molding stations radially arranged on said table corresponding to said gates, said molding stations being symmetrically arranged, a cradle and a hinge post at each said station, a lower mold casing supported thereby at each said station, a mold cover hingedly supported at said hinge post and adapted to form an enclosure with said lower mold casing, and means to lock said cover and said casing to form receptacles abutting said central reservoir.
4. In a centrifugal molding machine, in combination, a horizontal table rotatably mounted, means to rotate said table, a replaceable refrac-

tory block centrally mounted on said table, mold stations arranged radially and symmetrically on said table, mold supports at each of said molding stations, a mold casing comprising a lower mold support and a cover hingedly secured adjacent the outer periphery of said table at each said station, said mold support and cover defining a substantially cylindrical mold enclosure, molds of substantially cylindrical outer configuration received at each said mold station, a mold cavity within said mold defining the object to be cast, a basin of substantial size in said reservoir block, gates through said reservoir blocks aligned with each said mold station and communicating with said mold cavities, the outer surface of said reservoir block at each said mold station co-operating with said mold to form one face thereof, and means to secure said mold casing in closed position.

5. In a centrifugal casting machine, a horizontal table rotatably mounted, means to rotate said table, retaining means centrally disposed on

10 said table, a replaceable refractory reservoir block in said retaining means, mold stations arranged radially and symmetrically on said table, each said mold station including a cradle and a hinged post, a lower mold casing received in each said cradle, an upper mold casing hingedly attached to said mold post, said casing parts, when closed, defining a substantially cylindrical mold enclosure, a mold of substantially cylindrical outer conformation received in said mold casing and abutting said reservoir block, a basin of substantial capacity in said reservoir block, gates in said block communicating with said basin and said mold cavities, the outer wall of said reservoir block at each said station serving as one face of the mold cavity, said mold support being spaced from the upper surface of said table, and readily releasable means to lock said upper casing in its closed position.
